UNITED STATES PATENT OFFICE.

ISAAC S. PURCELL, OF OAK PARK, ILLINOIS, ASSIGNOR TO TENTOBED COMPANY, OF CHICAGO, ILLINOIS, A CORPORATION OF ILLINOIS.

FOLDING COT.

Application filed October 25, 1920. Serial No. 419,273.

To all whom it may concern:

Be it known that I, ISAAC S. PURCELL, citizen of the United States, residing at Oak Park, Illinois, have invented certain new and useful Improvements in a Folding Cot; and I do hereby declare the following to be a full, clear, and exact description of the invention, such as will enable others skilled in the art to which it appertains to make and use the same.

My invention relates to a frame for folding cots or the like, and in its general aspects aims to provide a frame construction which will afford unusual rigidity at all of its joints when the cot is erected, which will leave the constituent parts all interconnected when the frame is folded into a compact space, and which will maintain the relative rigidity of some of the constituent elements up to certain steps in the folding of the frame, so as to facilitate this folding.

More particularly, my invention aims to provide a frame construction of this general class which will readily lend itself to an all-metal construction, which will be adapted to afford a symmetrical frame with side rails close to the edges of the bed-bottom, and one in which the legs will be rigidly held in place when the cot is erected for use. Furthermore, my invention aims to provide a folding frame for a cot or other bed affording rigidity for the legs without employing cross-braces or connections of any kind between the two legs, which will automatically hold the end legs at right angles to both the side rail and end rail members of the frame both when the latter is erected and up to certain steps in the folding of the frame, which will automatically release the hold on these legs at certain points during the folding of the frame so as to permit the legs to be folded against normally horizontal frame portions, and in which the end and side rails will normally cooperate for holding the corner legs rigidly in their desired positions. Moreover, my invention aims to provide a folding cot frame construction in which the desired normal rigidity of the legs can be obtained by the use of simple and inexpensive hinge castings, aims to provide a lateral rigidity for the joints in the side rails for cooperating with the end

rails in holding the corner legs rigidly vertical, and aims to provide a folding cot in which the tension of the bed-bottom will normally cooperate with gravity in holding both the frame portion proper and the legs in their operative positions.

In some of its aspects, my invention relates to a folding cot suitable for outdoor use and adapted both for being folded into a compact space (such as will enable it to be carried conveniently on the running board of an automobile) and for supporting its own tent. Arrangements of this general class have been shown in U. S. Patents Nos. 1255224, 1285790, 1300872, 1285791 and 1286190 as all heretofore issued to me. However, these previously disclosed cot frame constructions have required transverse cross-bracing between the laterally opposed legs of the cot to hold the legs in their operative positions, and have also required auxiliary braces interposed between the end legs and the side rails for preventing the pivotally connected legs from moving about their pivots in the vertical planes of the adjacent side rails of the cot. My present invention aims to secure the desired stability and rigidity for the end rails without requiring cross-braces and more particularly aims to do this by clamping extensions of the end legs between adjacent portions of the end rails and of the side rails, and by stiffening the articulating joints in the side rails so that the latter will cooperate effectively in this clamping. Moreover, I aim to do this independently of the tension on the bed-bottom, thereby avoiding difficulties which might arise when the bed bottom stretches, and also aim to do this in such a manner as to facilitate both the folding and the erecting of the cot frame. Still further and more detailed objects will appear from the following specification and from the accompanying drawings, in which—

Fig. 1 is a side elevation of a folding cot embodying my invention.

Fig. 2 is an end elevation of the same. 100

Fig. 3 is a fragmentary plan view of the same.

Fig. 4 is a fragmentary view of the cot when folded, this figure being drawn on a larger scale and showing the folded positions of the side rail and legs at one side

of the cot, together with the means for connecting these elements to each other and to the end rails of the cot.

Fig. 5 is an enlarged section taken centrally and longitudinally through one end of a side rail member and the adjacent corner leg when the latter is folded against this side rail member, showing how the adjacent end rail normally cooperates with the hinge casting in maintaining the corner leg vertical.

Fig. 6 is a bottom view of the same parts, taken from the bottom of Fig. 5.

Fig. 7 is an enlarged end view of one of the end rails of the cot, showing a portion of a canvas bed-bottom attached to the same.

Fig. 8 is a diagrammatic view of the cot with the bed-bottom omitted, showing the arrangement of the legs and frame members when the cot is erected for use.

Fig. 9 is a similar diagrammatic view taken during the first step in the folding of the cot frame and showing how the corner legs are maintained in rigid position during this step of the folding.

Fig. 10 is a similar diagrammatic view showing the parts after each folded side rail member has been swung around the adjacent ends of the two end rails, thereby releasing the corner legs so that these can fold up against the adjacent side rail members.

Fig. 11 is an enlarged and vertical transverse section through one of the side rail hinges, taken along the correspondingly numbered line in Fig. 1 or Fig. 12.

Fig. 12 is a plan view of another embodiment of my invention, namely one in which the corner hinge castings are reversed in position from those of Fig. 3, so as to spread the side rails further apart and so that both of the side rails can be folded against the overlapped end rails without first swinging them around the tips of the latter.

Each of the end rails is pivotally connected at each end to the adjacent side rail members by a corner hinge member which (in the arrangement of Fig. 3) permits the adjacent side rail member to be swung 50 around the tip of the end rail substantially through an arc of 270° during the folding of the cot frame. For this purpose I desirably employ malleable iron castings 4 each substantially L-shaped in plan view, and each 55 having one end secured to the adjacent side rail member, while its other end is forked to afford a pair of arms 5 straddling the adjacent end rail. These arms 5 and 5^A are respectively disposed above and below 60 the adjacent end rail and are pivoted to the end rail by means of a pivot bolt 6 as shown in Figs. 1 and 2. Each of the said L-shaped hinge members has its forked portion equipped with a recess adjacent to the fork 65 proper, thereby leaving room for the inter-

posing of a leg extension 7 formed by the upper end of a casting 8 which is riveted to the adjacent corner leg 9 after the manner illustrated in Fig. 5. This casting 8 is pivoted to the L-shaped casting 4 on a pivot pin 70 10 disposed below both the adjacent side rail and end rail, after the general manner shown in Fig. 5, and the lower arm 5^A of the said L-shaped and forked casting is cut away as shown in the same figure to permit the extension 7 on the leg extension casting 8 to swing into and out of its said interposed position.

When the cot is erected, this extension 7 is disposed upwardly as shown in dotted 80 lines in Fig. 5, so that it is clamped between the adjacent end rail 2 and the part of the casting 4 which affords a closure for the pipe 12 of the adjacent side rail member. Consequently, this clamping of the part 7 (which 85 part forms a rigid extension for the leg 9) serves to hold this leg firmly against rocking upon its pivotal mounting, and since the casting 8 is pivoted with a close lateral fit between two downward fork parts 11 of 90 the casting 4, this leg-carrying casting will also be held against swinging transversely of the cot frame. Consequently, each such corner leg is rigidly held in position when the cot is erected, without requiring either 95 cross-connections between the adjacent legs, or braces between the corner leg and one of the adjacent rails of the cot frame.

Each side rail member of the cot as illustrated is articulated upon a horizontal 100 axis, so that it consists of two sections, desirably of substantially equal length and pivoted to each other by means of hinge castings 14. Thus a side rail section 12 may have its hinge end entered by a plug forming part of an L-shaped casting 15 which is pivoted to an upwardly extending fork on a cross-shaped casting 14 as shown in Fig. 4, while the latter casting likewise carries a plug extension 16 which is socketed in the adjacent end of the companion side rail section 12^A. The casting 14 also desirably has as one of its normally horizontal arms an upwardly open channel portion extending in the opposite direction from the said plug 16 and adapted to receive the adjacent end portion of the section 12 when the cot is erected, so as to aid in supporting the latter and so as to afford lateral webs 20 which engage 110 the sides of the other section to hold the two sections against such relative rocking laterally of the cot frame as might be permitted by lost motion at this hinge.

The casting 14 also is connected by a pivot pin 17 to one of the center legs 18 of the cot frame, and this leg 18 is here shown as connected by a folding brace 19 with the same rail section 12^A to which the hinge casting 14 is rigidly fastened. The brace 19 de- 125 130

sirably consists of two pivotally connected brace portions adapted to fold close to each other as shown in Fig. 4 and having a stop lug 21 on one of these brace portions adapted to engage the other part for limiting the opening of the brace.

With the parts thus arranged and with the corner legs 9 and the center legs 18 of equal length, the side rail sections 12 and 12^A can readily be disposed in alinement with each other when the cot frame is erected, and the braces 19 then hold the center legs rigid longitudinally of the cot frame. At the same time, the hinge connection at the pivot 17 holds each center leg against movement laterally of the cot, so that no bracing of the center legs is required transversely of the cot. Each brace 19 therefore cooperates with the hinge formed by the parts 14 and 15 in holding the adjacent side rail sections in rigid extension of one another, and the channel sides 20 cooperate with the hinge construction in preventing the side rail sections from swinging laterally of the cot about the hinge connection between them, thereby maintaining the side rails and end rails in proper right-angled relation to each other and firmly clamping the extensions on the end legs so as to maintain these legs in rigid vertical positions.

In folding the cot frame which is diagrammatically shown in Fig. 8, (the canvas bed-bottom being omitted from the three diagrammatic views to simplify the drawings) the left hand end rail in this figure (corresponding to the left hand end rail in Fig. 1) is lifted so as to double the side rail sections upon each other by a swinging movement after the manner shown in Fig. 9. While this is being done, the L-shaped connecting members at the corners of the cot frame hold the end legs rigid with respect to the adjacent frame portions, while the braces 19 likewise hold the center legs rigid. Consequently, no attention whatever needs to be paid to any of the legs while the cot frame is thus doubled upon itself. After this has been done, one after another of the side rail member can be swung clear around the adjacent end of the two overlapped end rails or through an arc of approximately 270°, in doing which the castings 4 automatically release the extensions on the end legs, while each brace 19 can be snapped shut by hand. Consequently, the legs can readily be folded close to the adjacent side rail sections, after the manner shown diagrammatically in Fig. 10 and shown more in detail in Fig. 4.

When the cot is erected, the tension of the bed-bottom continually urges the end rails towards each other and hence tends to force these end rails into clamping relation to the upward extensions 7 on the corner

legs, and also cooperates with the action of gravity on the hinged side rails in maintaining the horizontal frame portion in rigid rectangular formation. I am therefore able to provide an unusually rigid cot with a minimum of parts, while also utilizing some of the same parts for holding the legs rigid during part of the steps of folding the frame and hence making it easier for one man or woman to accomplish the folding or unfolding of the frame.

However, while I have illustrated and described my invention in a highly desirable embodiment, I do not wish to be limited to the details of the construction and arrangement thus disclosed, nor to its employment in connection with canvas-bottomed cots, it being obvious that various modifications might be made in the construction and arrangement without departing from the spirit of my invention or from the appended claims. For example, the general principles of my invention may be applied with equal facility in embodiments in which the L-shaped castings are reversed in positions from those shown in Fig. 3, thus connecting the end and side rails so that only a relative 90 degree movement about the corner hinges is required in erecting the cot frame or in folding the same.

I claim as my invention:

1. In a folding cot, a frame comprising frame members pivoted to each other at the corners of the frame, and legs each pivoted to one frame member adjacent to a corner of the frame and freely spaced from the other legs, each leg having an upward extension normally clamped between the two frame members forming the adjacent corner, whereby the said two frame members cooperate in holding the said leg in its normal position.

2. In a frame for a folding cot, an end rail member, a side rail member hingedly connected thereto and arranged for permitting the side rail to be swung around the tip of the end rail, and a leg pivoted to the hinge and having a portion normally clamped between adjacent portions of the two rail members to prevent the leg from moving about its pivotal mounting.

3. In a frame for a folding cot, an end rail member, a side rail member so hinged thereto as to permit the side rail to be swung with respect to the end rail in the general plane of the said frame, and a leg pivoted to one of the said members below both thereof and having an upward extension normally confined between portions thereof whereby the confining of the leg extension prevents the leg from moving about its pivotal mounting.

4. In a frame for a folding cot, an end rail, a fork straddling the end rail near the tip of the latter and having its arms re-

4
spectively above and below the end rail, means for pivoting both arms of the fork to the end rail on a vertical axis, a side rail fast upon the fork, and a leg pivoted to the 5 fork and having an extension normally confined between the end rail and a portion of the fork for preventing a movement of the leg about its pivot.

5. A frame for a folding cot, comprising 10 two side rail members each thereof consisting of a pair of sections disposed in substantial continuation of each other but spaced from each other, and a hinge connecting the two sections; two end rail members; hinges 15 respectively connecting the side rail sections and the adjacent tips of end and side rail members with each other, while spacing the said connected portions from each other; and corner legs respectively pivoted to the 20 side rail members at the tips thereof, each corner leg having an upward extension normally confined in the adjacent one of said spaces for preventing the leg from moving about its pivotal mounting.

25 6. A frame for a folding cot, comprising a pair of end rails, a pair of articulated side rails each pivotally connected at its opposite ends respectively to the end rails, the pivotal connection between the rails permitting 30 the same to be moved into extension of each other; legs pivoted to the frame substantially at the said connections between the side and end rails; and means associated with the last named connections for preventing 35 the legs from moving about their normal relatively transverse position, the said means being arranged for permitting free pivotal movement of the legs when the side

rails are folded upon their articulating joints and thereafter swung into positions 40 substantially parallel to the end rails.

7. In a folding cot, a frame comprising horizontal members pivotally interconnected at the corners of the frame, legs respectively pivoted to the frame adjacent to the pivotal corner junctures in the frame, and means associated with each of the said pivotal corner junctures for normally holding the adjacent leg in a vertical position, each of the said holding means being so arranged 50 as to release its hold on the adjacent leg when the frame parts associated therewith are moved substantially ninety degrees about their pivotal juncture.

8. In a horizontal folding cot frame, a 55 pair of end rails, a pair of side rail members spanning the same and pivotally connected thereto on vertical axes, each side rail member comprising two sections pivoted to each other on horizontal axes, corner legs pivoted each to one of the said members adjacent thereto and below the other thereof and each having an upward extension normally clamped between the last named two members, the said leg extension being released 60 from its clamping when the last named two members are relatively moved to a predetermined extent about their pivotal connection to each other, and means associated 65 with the pivotal junctures of the side rail sections for preventing such relative movement of the side rail and end rail members when the cot is erected.

Signed at Chicago, October 22nd, 1920.

ISAAC S. PURCELL.
